CLAIM

The ornamental design for a housing for electrical and electronic components as shown and described.

DESCRIPTION

1. Housing for electrical and electronic components
  2. Housing for electrical and electronic components
- 1.1 is a front view of a housing for electrical and electronic components showing our new design with a front cover open;
1.2 is a right side view thereof;
1.3 is a front, top, and right side perspective view thereof;
1.4 is a front, bottom and left side perspective view thereof;
2.1 is a front view of the housing for electrical and electronic components shown in Reproduction 1.1 with the front cover closed;
2.2 is a right side view thereof;
2.3 is a front, top, and right side perspective view thereof;
2.4 is a front, bottom and left side perspective view thereof
The broken lines shown in the drawings depict portions of the housing that form no part of the claimed design.
